UNITED STATES PATENT OFFICE.

BRAINARD CLARK, OF ROZELLE, NEW SOUTH WALES, AUSTRALIA.

COMBINED TOBACCO BOX AND HOLDER FOR CIGARETTE PAPERS.

1,413,391.

Specification of Letters Patent. Patented Apr. 18, 1922.

Application filed December 9, 1919, Serial No. 343,673. Renewed March 3, 1922. Serial No. 540,935.

To all whom it may concern:

Be it known that I, BRAINARD CLARK, subject of the King of Great Britain and Ireland, residing at "Lucknow," Victoria 5 Street, Rozelle, in the State of New South Wales, Commonwealth of Australia, have invented new and useful Improvements in a Combined Tobacco Box and Holder for Cigarette Papers, of which the following is 10 a specification.

Persons who are in the habit of making their own cigarettes are often inconvenienced owing to the fact that the small packages of paper, in which the tobacco is 15 rolled, become mislaid or through being kept in the clothes pockets the paper frequently becomes damp with perspiration, and in consequence thereof the gummed edges of the paper adhere to the next sheet 20 and become useless. It is with a view to overcome these difficulties that the present invention has been devised. The box provides a place for keeping the papers which 25 is convenient and at the same time protects them from outside moisture.

The invention may be applied to the ordinary tins in which many brands of tobacco are retailed to the consumer or it may be applied to a better class container which 30 would then be used in place of the ordinary pouch. It has been designed for use particularly with that class of paper which is packed zig-zag fashion in a package having a longitudinal opening through which each 35 succeeding sheet will protrude as the top one is withdrawn from the package.

The invention consists of a box, in which the tobacco is held and provided with, preferably, a hinged lid within which is a central longitudinal recess adapted to receive 40 the package of papers. A cover plate of suitable material such as tin is provided, having a longitudinal opening at or near its centre which fits into the lid over the package of papers in such a way that the sheets of paper will protrude and may be pulled through the opening in the cover plate, one at a time as they are required.

In the accompanying sheet of drawings, 50 Fig. 1 is a plan of the box with the lid thrown open.

Fig. 2 is a sectional elevation taken on the line A. B. of Fig. 1.

1 is the box in which the tobacco is packed, 2 the flanged lid thereof, 3 the hinge, 4 the recess formed by depressing a portion of the body of the lid, 5 the package of papers within the recess, 6 the cover plate which is frictionally held within the lid flange 10 against accidental displacement and by which the package of papers is held in position within the recess, 7 the longitudinal opening in the cover plate, 8 the sheet of paper protruding through the opening 7, while 9 is an indentation stamped in the flange 10 of the lid for the purpose of assisting in holding the cover plate 6 in position.

For some purposes it may be desirable to dispense with the cover plate 6 and provide other and cheaper means for securing the package of papers 5 in the recess 4. One method would be to so shape the longitudinal edges of the recess as to grip the package when it is pressed into the recess.

I claim:

In combination with a receptacle lid having a continuous marginal flange projecting laterally therefrom, the said lid having a depression formed therein extending from one flange to the opposite flange, said depression forming a seat for receiving and retaining a package of cigarette papers in position, a flat cover plate snugly fitted and frictionally held within the flange of the lid and adapted to overlie and abut a package of cigarette papers to maintain the latter in position in the depression, said cover plate having a longitudinal slot in the portion which overlies the package of cigarette papers permitting withdrawal of the papers one at a time, and retaining members formed on the flange for engaging and removably retaining the cover plate in position.

In testimony whereof I have signed my name to this specification in the presence of two subscribing witnesses.

BRAINARD CLARK.
